Inventor,

John David Browne

United States Patent Office.

JOHN DAVID BROWNE, OF CINCINNATI, OHIO.

Letters Patent No. 82,287, dated September 22, 1868.

IMPROVEMENT IN SASH-PULLEYS.

The Schedule referred to in these Letters Patent and making part of the same.

TO ALL WHOM IT MAY CONCERN:

Be it known that I, JOHN DAVID BROWNE, of the city of Cincinnati, in the county of Hamilton, and State of Ohio, have invented a new and useful Improvement in the Construction of Window-Sash Pulleys; and I do declare that the following is a full, clear, and exact description of the construction of the same, reference being had to the annexed drawing, making part of this specification, in which—

Figure 1 is a perspective view of the face-plate, with the improvements, having one side of the case attached to it.

The nature of my improvement consists in the mode of so forming the front or face-plate, by which means the drilling of the holes for the securing the sides of the case to the face-plate, as hitherto done, is dispensed with, thus considerably reducing the cost of making.

A represents the face-plate, having the lugs *a* cast on it, to which the side plates B are attached, to obviate the necessity of drilling holes to receive the pins or rivets. I make a projection, *c*, on the lugs *a*, the base of the lug being set even or level with the end of the slot *b* in the face-plate, through which the roller passes. The projections *c*, on the lugs, overhanging the slot *b*, form recesses, in which the pins or rivets are securely held, to secure the case-plates B, which may be made of any of the forms generally used for that purpose.

What I claim, and desire to secure by Letters Patent, is—

The recessed lugs *a* of the face-plate A, in combination with the holding-pins or rivets of the case-plate B, in the manner substantially as described, and for the purpose set forth.

JOHN DAVID BROWNE.

Witnesses:

JOHN W. CARTER,
B. F. STANLEY.
